PRESS PROVIDED WITH AT LEAST ONE DIE FOR MOULDING PRODUCTS FROM CERAMIC MATERIAL

Hendrik Jan van den Berge, Nico Blieck, Johannes Jochem Willem Geleijns, and Adrianius Theodorus van der Maat, all of Eindhoven, Netherlands, assignors to North American Philips Company, Inc., New York, N.Y., a corporation of Delaware

Filed Dec. 18, 1958, Ser. No. 781,298

Claims priority, application Netherlands Jan. 3, 1958
8 Claims. (Cl. 25—45)

This invention relates to presses for moulding products from ceramic material.

According to the invention, such a press is characterized in that it contains a duct through which the ceramic material is fed to the die or dies as a suspension in a liquid preferably having a low viscosity, means being provided for the discharge of the liquid during the pressing process. Feeding the material and filling the dies is materially facilitated by the use of the invention and furthermore other difficulties such, for example, as the formation of clouds of dust of the finely divided or pulverized material are avoided. Since in accordance with the invention special means are provided for drawing off the liquid during the moulding process, the punches may accurately fit in the dies.

According to one embodiment of the invention provision is made of at least one die open at two ends which during the moulding operation is closed at one end by a punch and at the other end by a filter. This embodiment of the invention provides the advantage that the moulded articles can readily be taken out since after the removal of the filter or filters they can be pressed out of the die or dies by a further movement of the punch or punches. In a further embodiment of the invention the filter comprises a perforated plate provided with a porous cover.

In a still further embodiment of the invention provision is made of at least one die open at two ends which is closed on both sides by movable punches which have, at least at one side, discharge ducts for the suspension liquid which are closed by a porous cover. In some cases the discharge of the suspension liquid is facilitated and accelerated by this embodiment of the invention.

In another embodiment of the invention the punches are secured to a pressing plunger which is provided with a duct which extends in the direction of length of the plunger and is provided with a check valve and through which the suspension is periodically fed to the dies. Thus, the use of resilient means for feeding the suspension to the dies is minimized while the construction of the device is simplified.

In still another embodiment of the invention the press includes a reciprocating closing member containing a duct for discharging the suspension liquid, and furthermore a moulding plate adapted to be moved in the same directions and provided with at least one preferably exchangeable die, the filter being arranged between the closing member and the moulding plate, while the likewise reciprocating pressing plunger, which carries the punches, passes through the moulding plate in a liquid-tight manner. This embodiment of the press has the advantage that the filter can readily be replaced when it is clogged, while the dies are sealed on one side in a simple manner and furthermore the moulded products are readily accessible.

In a further embodiment of the invention the press is preferably designed so that between the side of the dies facing the plunger seal and this seal there is a space in which the punches can be accommodated entirely, the surfaces of the upper sides of the punches when projected onto a plane at right angles to the plunger centre line

2

together being about equal to the cross sectional area of the plunger. The advantage of this embodiment consists in that the dies are filled more satisfactorily and furthermore the suspension does not seep between the punches and the die wall since the volume of the suspension remains substantially constant.

It is known to subject ceramic material to the influence of a magnetic field during a moulding operation. The press in accordance with the present invention is particularly suited for carrying out this method, if, in accordance with a further embodiment of the invention, the dies are made of a non-magnetizable material while coils which in operation pass an electric current, are arranged in the closing member surrounding the dies so that the ceramic material is subjected to the influence of a magnetic field during the moulding process.

In order that the invention may readily be carried out, an embodiment thereof will now be described, by way of example, with reference to the accompanying drawings, in which

FIG. 1 is a cross-sectional view of a hydraulic press taken along a vertical plane,

FIG. 2 is a cross-sectional view taken along the line 2—2 of FIG. 1, and viewed in the direction of the arrows, and

FIG. 3 shows diagrammatically a modified embodiment of a part of the press shown in FIG. 1.

In the figures, reference numeral 1 designates a cylinder in which a moulding plunger 2 can move. The cylinder 1 forms part of a frame on which cylinders 3 and plungers 4 are provided. The main plunger 2 has a cylindrical part 5 to which two punches 6 are secured. The plungers 4 are rigidly connected to a moulding plate 7 containing an annular member 8. A vertical rim 9 of this annular member 8 embraces dies 10 and another cylindrical member 11 in which a rubber ring 12 is enclosed for sealing the plunger part 5. A space 13 is left between the lower sides of the dies 10 and the seal 12. At the upper end of the press provision is made of two pressing cylinders 14 and plungers 15. These plungers 15 are secured to a closing member 16 which contains a second annular member 17. This annular member 17 encircles a plate 19 provided with apertures 18, the closing member 16 having an aperture 20. Between the closing member 16 and the moulding plate 7 there are interposed a centrally perforated metal plate 21 and a filter 22. The main plunger 2 and the part 5 of this plunger contain a bore 23 and a check valve 23a. The cross-sectional area of the cylindrical part 5 is about equal to the sum of the surfaces of the punches 6 designated A.

At the beginning of the moulding cycle the moulding plate 7 is supported by the plungers 4 which act as hydraulic buffers and by the cylinders 3, and there is a clearance between the moulding plate 7 and the closing member 16. The die cavities are entirely open. Subsequently the closing member 16 together with the filter is pressed by the plungers 15 onto the moulding plate 7 and, the suspension is then fed to the dies. When the supply of suspension is sufficient, the plungers 15 press the closing member 16 and the moulding plate further downwards, the plunger 2 still being stationary, so that the punches 6 are pressed into the die cavities and the suspension liquid is expelled. When the products have been formed in this manner, the plunger 2 moves upwards and by this upward movement and by buffer action of the plungers 4 the moulding plate 7 and the closing member 16 are also moved upwards. When a certain position is reached, the plungers 4 become inoperative; however, the plunger 2 continues its movement, the moulding plate 7 being stationary, and the products are pressed out of the die cavities, the closing member 16

being likewise pressed upwards. When the products are entirely pressed out of the die cavities, the plunger 2 stops; the plungers 15 move the closing member 16 slightly further upwards so that the products can be removed. Finally the plunger 2 moves downwards and the moulding cycle can be repeated.

Obviously, by means of the described press articles can be moulded which have a different arbitrary cross section or are provided with tags, flanges, lugs and similar projecting parts. In this event, the dies must be designed so that these articles can be removed therefrom, for example by the use of split dies or in some other known manner.

The entire closing plate 16 may be omitted and replaced by a second moulding plate 26, as is shown diagrammatically in FIG. 3, provision being made of a second pressing plunger 27 which is provided with apertures 28 and carries a filter 30 at the pressing end of counterpunches 29 provided on the pressing plunger 27. Thus, a moulding pressure is exerted on the suspension from both sides, so that the speed of the process is increased. Alternatively the punches 6 and the pressing plunger 5 may be apertured, a filter being arranged on the upper ends of the punches 5.

In the press shown, cavities 24 and 25 are provided both in the moulding plate 7 and in the closing member 16. Heating or cooling elements may be provided in these cavities, if this should be required or desirable for the material to be moulded. Alternatively, coils passing an electric current may be disposed in these cavities, the edges of the moulding plate 7 and the closing member 16 and the dies being made of a non-magnetizable material so that the ceramic material can in a known manner be exposed to the influence of a magnetic field during the moulding process, a certain orienting influence being exerted on the suspended ceramic material.

What is claimed is:

1. A press for moulding ceramic products in a mould open on both ends comprising a plunger reciprocating through one end of said mould, a closing member adjacent to the other end of said mould, said closing member being provided with apertures forming a complete passage through said closing member, a filter interposed between said closing member and said mould a space in said press communicating with said mould, duct means in said plunger extending longitudinally thereof and opening into said space, through which ceramic material is fed as a liquid suspension to completely fill said space and said mould, means to move said mould to reduce the volume of said space and thereby concentrate the suspension in said mould prior to the molding operation proper, said apertures being the means for discharging the liquid during said mould movement and the moulding operation proper, said mould during the moulding operation being closed at one end by said plunger and at the other end by said filter.

2. A press for moulding ceramic products as claimed in claim 1 wherein said filter comprises a perforated plate and a porous cover overlay.

3. A press for moulding ceramic products as claimed in claim 1 wherein said duct means is a duct which extends the length of said plunger and including a check valve through which said liquid suspension is fed periodically to said mould.

4. A press for moulding ceramic products in a mould open on both ends comprising a plunger reciprocating through one end of said mould, a closing member adjacent to the other end of said mould, said closing member being provided with apertures forming a complete

passage through said closing member, a filter interposed between said closing member and said mould, and duct means through which ceramic material is fed to the mould as a liquid suspension, said apertures being the means for discharging the liquid during the moulding operation, and said mould during the moulding operation being closed at one end by said plunger and at the other end by said filter, and a space communicating with said mould and accommodating the head of said plunger, means to move said mould to decrease the volume of said space thereby concentrating the suspension in said mould, said plunger operatively associated with said mould to eject molded material therefrom.

5. Apparatus comprising a press, at least one die means operatively associated with corresponding punch means at one side thereof and filter means operatively associated with said die at the other side thereof, a space in said press communicating with the die cavities, means to fill said space and said die cavities with a solid suspension, means to move said die to decrease the volume of said space and thereby concentrate said suspension in said cavity by forcing liquid through said filter means and means to move said punch to mold said concentrate within said die and expel the suspending liquid through said filter.

6. Apparatus according to claim 5 wherein said die is open ended and said punch is arranged to pass into said die cavity whereby said molded material is ejected from the die.

7. Apparatus comprising at least one die member having an open ended die cavity, a movable mold member supporting said die member, said movable mold member defining a space communicating with said die cavity at one end of said die member, punch means operatively associated with said space and movable relative to said mold member, movable closure means including filter means operatively associated with said die member to close the other end of said die cavity, means adapted to supply a solid suspended in a liquid to said space and said die cavity means adapted to supply a solid suspended in a liquid to said mold member in fluid tight relation and move said closure means and said mold member relative to said punch means to reduce the volume of said space and register said punch means with said die member to close the adjacent end of said die cavity whereby said die cavity is filled under high pressure with highly concentrated solids suspension, means to move said punch means relative to said closure means and said mold member and into said die cavity to further compact said solids in said die cavity and substantially completely separate said solids and suspending liquid, said liquid being withdrawn through said filter means.

8. Apparatus according to claim 5 wherein said punch means are adapted to eject said molded material from said die.
